STRUCTURAL PANEL

Norman J. Haskins, Melrose Park, Ill., assignor to The Erie Enameling Company, Erie, Pa., a corporation of Pennsylvania

Filed Jan. 7, 1960, Ser. No. 1,102

1 Claim. (Cl. 189—34)

This invention relates to structural panels, and more particularly, to an improved structural panel wherein a separation is provided between the metallic outside members on opposite sides of the panel and an improved insulation is provided.

In previous panels of the type disclosed, the panel members on opposite sides were in engagement with each other so that a transfer of heat by conduction from one said panel member to the other resulted. This caused a substantial heat loss even though the insulation between the steel panel members was of a proper design for heat loss and fire resistance.

It is, accordingly, an object of the invention to provide an improved panel wherein several layers of insulation therein will remain rigidly fastened to each other under all conditions and wherein the outside metallic panel members are held in spaced relation from each other.

Another object of the invention is to provide a panel which is simple in construction, economical to manufacture and simple and efficient to use.

With the above and other objects in view, the present invention consists of the combination and arrangement of parts hereinafter more fully described, illustrated in the accompanying drawing and more particularly pointed out in the appended claim, it being understood that changes may be made in the form, size, proportions, and minor details of construction without departing from the spirit or sacrificing any of the advantages of the invention.

In the drawing:

FIG. 1 is a view of a panel according to the invention; and

FIG. 2 is an isometric view with one end shown in cross section similar to FIG. 1.

Now with more particular reference to the drawing, the panel is made of two panel member casings 11 and 12 which are in the form of open faced containers with their open sides facing each other and one fitted into the other. These containers may be made, for example, of sixteen gauge steel with porcelain enamel ground coat plus one finish coat of porcelain on the fixture.

The two panels 11 and 12 are held together by screws 13 which are threadably inserted into flanges 15 and 16 of the inner panel member 12. The screws 13 may be self-tapping screws which enter a plain hole in the side flanges 19 and 16 of the panel. Each screw 13 has a flat head 17 which is received in an embossed portion 18 of a hole in the side flanges 19 and 16 of the panel.

The insulation between the two panel members 11 and 12 is made up of two layers of mineral type board which may be, for example, five-eighths inch gypsum wall board having a one hour fire rating with aluminum foil sheets 21 and 22 on each inner surface of the gypsum board. The

2

gypsum board is abutted against the inner surface of the metal and may be attached thereto. The aluminum foil may be attached to the wall board by suitable cement or it may be held thereto by friction due to the force of fiberglass material 24. The fiberglass material 24 may be in the form of a bat of material or the like.

In order to close the exposed open face between the panels between the side flanges 19 and 16, a pressure sensitive vinyl tape 26 is adhesively attached over a side 10 27 of the panel and it lies over and engages the flange 19 at 28, completely closing the space between the side edges of the two panels.

By providing the panel as disclosed and claimed herein, a panel which has a fire resistance of several hours is provided wherein heat is not conducted from one panel member to the other and an efficient insulation is provided therebetween.

The foregoing specification sets forth the invention in its preferred practical forms but the structure shown is 20 25 capable of modification within a range of equivalents without departing from the invention which is to be understood is broadly novel as is commensurate with the appended claim.

The embodiments of the invention in which an exclusive property or privilege is claimed are defined as follows:

A panel for use in building construction and refrigerators comprising two side members in the form of flat metallic plate like members having their edges and ends 30 turned up to form two containers open at one side, one said container being received in the other with its open side towards the other said container providing an enclosure, an insulation material in said enclosure, said insulation material comprising two spaced outer layers of 35 mineral type wall board with a layer of fiberglass therebetween, a layer of bright metal foil between each said wall board and said fiberglass, said one container being smaller than the other and leaving a space between the outer wall of one said member and the inner wall of the other, said insulation material fitting snugly into said one container filling said one container, embossed holes 40 in the outer member walls registering with holes in the inner member, flat head screws in said embossed holes engaging said inner member and holding the side walls of 45 said two members in spaced relation to each other, and a vinyl tape member overlying the outer wall of one said member and the outer surface of the bottom panel of the other said member.
